PICKER STICK CHECK

Frank P. Medeiros, Fall River, Mass., assignor of
one-third to Antonio S. Aguiar, Swansea, and
one-third to William Hunt, Fall River, Mass.

Application August 3, 1943, Serial No. 497,254

8 Claims. (Cl. 139—164)

The present invention relates to textile looms, and has particular reference to a novel construction for a picker stick check.

It is the principal object of the invention to provide a picker stick check which has a rolling impact surface.

Another object of the invention is to provide a check of rugged construction and long life which may be readily mounted on any type of loom.

A further object is to provide a check which engages the picker stick with a yielding resistance and prevents excessive wear and breakage of the picker stick.

Still another object of the invention is to provide a simple and inexpensive arrangement for adjusting the yielding resistance of the check to accord with the movement and the speed of the picker stick.

With the above and other objects and advantageous features in view, the invention consists of a novel arrangement of parts more fully disclosed in the detailed description following, in conjunction with the accompanying drawing, and more specifically defined in the claims appended thereto.

In the drawing,

Fig. 1 is a plan view of the novel picker stick check;

Fig. 2 is a side view thereof; and

Fig. 3 is an end view thereof.

It has been found desirable to provide an arrangement for increasing the life of a picker stick check and for minimizing wear on the picker stick and resulting breakage. Checks of the metal impact type which are designed to receive the full impact of the picker sticks have the disadvantage that there is excessive wear of the picker stick and frequent replacement is necessary; and checks of the leather strap type stretch and become loose and require frequent adjustment and replacement.

To obviate these disadvantages I have devised a check which provides a rolling impact surface against which the picker stick strikes, with the further advantage that the stick is shifted slightly laterally on impact to increase the rolling friction, and I have provided a resilient end stop for completing the stoppage of the picker stick, the end stop being adjustable to obtain the proper amount of resistance to the picker stick movement.

Referring to the drawing, the novel check comprises a base 10 of cast iron or other durable material, which carries a roller assembly 11 and

an end stop arrangement 12. The roller assembly consists of at least one, and preferably two roller drums 13, rotatably mounted on a shaft 14 and keyed thereon against axial movement in any suitable manner, the roller drums preferably having an outer facing or shell 15 of resilient material such as rubber.

The roller assembly is preferably mounted on the base by providing a recess 16 in the base for 10 accommodating the roller drums 13, to expose only the upper portion thereof for impact, and by providing aligned bearing recesses 17 for receiving the ends of the shaft 14, bearing caps 18 being positioned over the shaft ends and the bearing recesses and secured to the base by screws or the like to securely lock the shaft in place. The roller assembly is mounted on the base so as to be in parallel alignment with the side edge 19 of the base.

20 Referring now to Fig. 2, it will be noted that the side edge 19 is preferably angularly disposed to the plane of the base so that the end stop arrangement 12 is positioned to extend over and slightly overhang the roller drums. The end stop arrangement illustrated includes a plurality of resilient fingers 20, secured at their lower ends to the side edge 19 by any suitable means such as screws or the like, each finger 20 consisting of a selected number of separate spring strips 21 which cooperate to form a laminated spring finger of a desired resilience. The spring fingers are thus aligned with the roller drums in overhanging relation and are spaced sufficiently adjacent thereto to be contacted by the picker stick immediately after the stick impacts the roller drums, thus preventing the stick from over-running the drums and becoming wedged or locked against return movement.

25 The base is mounted on the loom race in the path of movement of the picker stick, a preferred mounting including an angle iron 22 which is secured to the lower face of the base by a holding bolt 23; the base end 24 of the angle iron is provided with a bolt opening 25 and the base has an elongated bolt slot 26 extending vertically to permit a vertical and an angular setting. The other end 27 of the angle iron is recessed as indicated at 30 28 to slidably seat in the correspondingly shaped end 29 of a second angle iron 30, see Fig. 3, the end 27 having a bolt slot 31 and the end 29 having a bolt opening 32 to receive a holding bolt 33, the slidable seating permitting a vertical adjustment of the base. The other end 34 of the

angle iron 30 is provided with suitable openings 35 for attachment to the loom race.

The operation of the novel check may now be explained. The angle iron 30 is secured to the loom race in approximately the position to bring the roller drums in line with and directly in the path of movement of the picker stick at the end of its stroke, thus providing a substantial area for impact by a substantial length of the picker stick and the angle iron 22 and the base are adjusted and set so that the picker stick slidingly impacts the roller drums, which turn with the impact, and is brought to a stop by the stop fingers 20. The impact is a rolling impact, and the roller drums force the picker stick slightly laterally so as to provide an increasing rolling resistance to the continued movement of the stick, which is brought to a full stop by the yielding resistance of the laminated spring fingers. The adjustable setting permits the check to be mounted, if desired, so that the lateral thrust of the check causes the stick to slidingly engage the side of the loom race or loom frame, to thus partially or completely stop the inward movement of the stick.

Although I have described and illustrated one preferred embodiment of the invention, it is obvious that changes in the size, shape, and material of the parts, and in their relative arrangements, may be made to suit the requirements for different loom types, without departing from the spirit and the scope of the invention as defined in the appended claims.

I claim:

1. A picker stick check, comprising a base, a roller assembly mounted thereon including a rotatable drum, said base having means for adjustably securing to a loom, whereby the rotatable drum is positioned to be impacted by the picker stick, and a stop device on said base positioned adjacent the rotatable drum and adapted to be impacted by the picker stick subsequent to the impacting of the rotatable drum.

2. A picker stick check, comprising a base, a roller assembly mounted thereon including a rotatable drum having a resilient facing, said base having means for adjustably securing to a loom, whereby the rotatable drum is positioned to be impacted by the picker stick, and a stop device on said base positioned adjacent the rotatable drum and adapted to be engaged by the picker stick subsequent to the impacting of the rotatable drum.

3. A picker stick check, comprising a base, a roller assembly mounted thereon including a rotatable drum, said base having means for adjustably securing to a loom, whereby the rotatable drum is positioned to be impacted by the

picker stick, and a resilient stop device on said base positioned adjacent the rotatable drum and adapted to be engaged by the picker stick subsequent to the impacting of the rotatable drum.

4. A picker stick check comprising a base having means for adjustable mounting on a loom, a roller assembly comprising a drum rotatably mounted on a shaft, said base having a recess for receiving the lower portion of the drum and bearings for the shaft ends, whereby the upper portion of the drum extends above the base to be impacted by a picker stick, and a stop device mounted on said base in adjacent alignment to said drum.

5. A picker stick check comprising a base having means for adjustable mounting on a loom, a roller assembly comprising a drum rotatably mounted on a shaft, said base having a recess for receiving the lower portion of the drum and bearings for the shaft ends, whereby the upper portion of the drum extends above the base to be impacted by a picker stick, and a stop device consisting of a plurality of spring elements mounted on said base in adjacent alignment to said drum and extending above the drum for engagement by the picker stick subsequent to impacting the drum.

6. A picker stick check comprising a base having means for adjustable mounting on a loom, a roller assembly comprising a drum rotatably mounted on a shaft, said base having a recess for receiving the lower portion of the drum and bearings for the shaft ends, whereby the upper portion of the drum extends above the base to be impacted by a picker stick, said drum having a rubber facing, and a stop device mounted on said base in adjacent alignment to said drum.

7. A picker stick check comprising a base adapted to be secured to a textile loom in parallel adjacency to the path of movement of the picker stick, a roller drum rotatably secured to said base, the axis of rotation of the roller drum being inclined to the path of movement of the picker stick, whereby the drum is progressively impacted by the picker stick at the end of the picker stick stroke, and resilient stop means adapted to engage the picker stick after it has impacted the drum.

8. A picker stick check, comprising a base, a roller assembly mounted thereon including a rotatable drum, said base having means for adjustably securing to a loom, whereby the rotatable drum is positioned to be impacted by the picker stick, and a resilient stop device positioned adjacent the rotatable drum and adapted to be engaged by the picker stick after it has impacted the drum.
